UNITED STATES PATENT OFFICE.

IRA A. MANN, OF PITTSBURGH, PENNSYLVANIA.

PLUMBING-FIXTURE.

1,067,533.

Specification of Letters Patent. Patented July 15, 1913.

Application filed June 11, 1912. Serial No. 703,043.

To all whom it may concern:

Be it known that I, IRA A. MANN, a citizen of the United States, residing at Pittsburgh, in the county of Allegheny and State 5 of Pennsylvania, have invented certain new and useful Improvements in Plumbing-Fixtures, of which the following is a specification.

The invention relates to plumbing fixtures, and particularly to connections for what are known as wall outlet fixtures, that is, fixtures hung or supported from the wall or against the wall, as opposed to those in which the support is from the floor. The 10 invention is illustrated as applied to a closet, but it will be understood that the construction is applicable to all kinds of plumbing fixtures employing bowls or receptacles. This application is in part a continuation of 15 my prior application which has matured into Patent No. 1,017,437. The invention has for its principal objects; the provision of a construction having an improved form of joint connection between the bowl and 20 outlet pipe, or soil pipe as it is termed in the art; the provision of a joint connection of the character specified which can be adjusted and made absolutely tight with a metal contact; and the provision of an improved joint construction which shall be of great strength and rigidity, so that if desired the entire weight of the bowl may be 25 supported directly from the soil pipe by virtue of this rigid joint connection. Certain 30 embodiments of the invention are illustrated in the accompanying drawings, wherein—

Figure 1 is an assembled view in section through the joint connection and illustrating the manner of supporting the bowl upon the coupling and against the partition, Fig. 2 is an enlarged sectional view of the end of the soil pipe with the coupling therein, Fig. 3 is a section through a modified form 45 of joint connection, Figs. 4, 5 and 6 are detailed views of the joint construction of Figs. 1 and 2, Fig. 4 being a section through that portion of the joint connection lying in the bowl, Fig. 5 being a side elevation of 50 the coupling member, and Fig. 6 being a plan view of the construction as shown in Fig. 4. Figs. 7 and 8 are detail views of a tool which may be employed in positioning the coupling or coupling member shown in 55 Fig. 5, Fig. 7 being a section through the tool, and Fig. 8 being an end view thereof,

Figs. 9, 10 and 11 12 are detail views of a modified form of joint construction, Fig. 9 being a section through the annular member secured in the bowl, Fig. 10 a side elevation of the coupling, Fig. 11 a section through the tool employed in positioning the coupling and Fig. 12 an end view of the tool of Fig. 11, Figs. 13, 14, 15 and 16 are detail views of still another modified form 60 of joint connection, Fig. 13 being a section through the joint member in the bowl, Fig. 14 being a side elevation of the coupling, Fig. 15 being an end view of the construction of Fig. 13, and Fig. 16 an end view of 65 the coupling of Fig. 14. Figs. 17, 18, 19 and 20 are detail views of another modified form 70 of joint construction, Fig. 17 being a section through the joint member in the bowl, Fig. 18 being a side elevation of the coupling, Fig. 19 being an end view of the joint member of Fig. 17, and Fig. 20 being an end 75 view of the coupling member of Fig. 18, and Figs. 21 and 22 are longitudinal sections through other modified forms of joint 80 construction.

Referring to Figs. 1, 2, 4, 5 and 6, 1 is the bowl of a wall closet having an outlet passage 2 and resting in position opposite a partition 3; 4 is a soil pipe located back of 85 the partition 3 and having a vent pipe 5; 6 is what may be termed a bearing plate, which bearing plate is secured to the wall and piping and assists in supporting the bowl in the manner illustrated, such bearing 90 plate construction being more particularly shown and described in my application Serial No. 667,813, filed December 26, 1911; 7 is an annular joint member rigidly mounted in the bowl at the outer end of the outlet 95 passage 2; and 8 is a coupling or coupling member secured at one end in the annular member 7 and at the other end in the outlet or soil pipe 4.

The construction of the joint member 7 100 will be apparent from Figs. 4 and 6. This joint member is of metal and is seated in an enlargement at the outer end of the outlet passage 2, lead or other similar packing 9 being inserted between the side of the annular member 7 and the interior surface of 105 the said enlargement. The joint member 7 is provided with lugs 10 (Fig. 6) to prevent the rotation of the member 7, and provide an enlarged support for the packing there- 110 above, the enlargement in the bowl being correspondingly cut out to receive such lugs

as indicated in Fig. 6. The member 7 is provided with the inclined grooves 11 adapted to receive the lugs 12 carried by the coupling member 8 and the member 7 is also provided with a beveled portion 13 corresponding to the beveled portion 14 of the coupling 8, the arrangement being such that a partial rotation of the member 7 with respect to the member 8 will cause the beveled 10 surfaces 13 and 14 to be forced tightly together. The inclination of the grooves 11 is such that only a fraction of revolution of the bowl and the member 7 carried thereby is necessary in order to bring the beveled 15 surfaces tightly together. This is advantageous, as in some cases it is not possible to give the bowl a full revolution because of the interference with the floor. The lugs 12 and grooves 11 constitute an interrupted 20 quick screw connection. The outer portion of the coupling 8 is screw-threaded into the end 15 of the soil pipe as indicated in Fig. 2 and is locked in position by means of a nut 16 which fits into a recess in the end of the 25 part 15 as indicated in Fig. 2. This nut 16 is of a relatively soft packing material such as lead and screw threaded to fit the threaded portion of the coupling 8, and after the coupling member 8 has been brought to 30 its proper position this packing nut 16 can be screwed down to position and tamped tightly into position, thus making an absolutely tight joint between the soil pipe and coupling and prevents any rotation of the 35 coupling with respect to the soil pipe when the bowl is screwed onto the other end of the coupling. The provision of the packing 16 in the form of a nut constitutes a convenient means for positioning such packing, but if desired the packing might be poured into the recess while hot, or positioned in any other desired manner.

The tool shown in Figs. 7 and 8 can be utilized in adjusting the coupling member 45 of its proper position in the soil pipe. This tool 17 is provided with a head 18 for engaging a wrench and has upon its interior a beveled surface 19 corresponding to the bevel 13 on the annular member 7 and also 50 has grooves 20 corresponding to the grooves 11 on the annular member 7. When the tool 17 is screwed upon the end of the coupling 8 and such coupling 8 is screwed into the soil pipe until the flange 21 on the tool 55 comes flush with the outer face of the partition, the position of the coupling 8 is fixed and if the tool is then removed and the bowl secured in position its bearing face will fit against the partition when the surfaces 13 60 and 14 of the annular member 7 and coupling come together. The tool is provided with a mark 22 which serves to indicate the proper rotative position of the lugs 12. When the coupling 8 has been screwed to its 65 proper position in the soil pipe the packing

nut 16 is securely tamped into position thus preventing any further rotating of the coupling in either direction and providing a tight joint between the coupling and soil pipe. The coupling member is thus accurately and rigidly secured in its proper position of adjustment.

In the construction shown in Fig. 3 the annular joint member 23 is maintained securely in position in the bowl by means of the lead packing 24 and a tight joint is secured between the coupling 25 and the member 23 by means of the packing ring 26 of lead or other suitable material which is compressed against the member 23 and against the coupling 25 by the ring 26', such ring 26' being pulled inward by means of the studs 27. The sides of the packing ring 26 are inclined and a notch provided in the outer face in order to secure a more ready crowding inward of the packing when the ring 26' is drawn inward by the studs 27. The end 15 of the soil pipe is connected to the end of the coupling 25 in the manner heretofore described, the nut 16 being of 90 packing material.

Figs. 9 and 10 illustrate another form of construction which may be employed in lieu of the construction shown in Figs. 4, 5 and 6. In this construction the interior of the joint member 28 which is secured in the bowl is provided with ordinary screw-threads 29 with which the screw-threads 30 on the coupling member 31 coöperate, the ordinary continuous screw connection thus taking the place of the interrupted quick screw connection of the structure of Figs. 4, 5 and 6. The coupling 31 is moved to position by means of a tool 32 corresponding in function to the tool 17 of Figs. 7 and 8, such tool having upon its interior threads 33 adapted to fit the threads 30 of the coupling 31.

The coupling illustrated in Figs. 13, 14 and 15 is quite similar to that of Figs. 4, 5 and 6, the primary difference being in the use of an ordinary nut 34 which is provided upon the coupling member 35 instead of the packing nut 16 of the construction of Fig. 2, such nut 34 being adapted to screw against the end of the soil pipe. Another feature of distinction in this form of connection as compared with the construction of Figs. 4, 5 and 6 resides in the placing of the beveled portion 36 in advance of the lugs 37 which is the reverse of the arrangement shown in Figs. 4, 5 and 6. The lugs 37 in this construction coöperate with the slots 38 and serve to draw the beveled surface 36 tightly in engagement with the beveled surface 39 on the annular joint member 40. The annular joint member 40 is provided with lugs 41 corresponding to the lugs 10 shown in Fig. 6 and the member 39 is secured in position in precisely the same man- 130

ner as the member 7 of Fig. 4. The nut 34 not only serves to make a tight joint between the coupling 35 and the soil pipe but also tends to prevent rotation of the coupling member with respect to the soil pipe. In order to still further guard against the rotation of the coupling member 35, its outer surface is grooved as indicated at 41 and in these grooves are fitted keys 42. After the coupling 35 has been screwed to position these keys are driven down in the grooves and cut into the threads on the soil pipe thus effectually preventing rotation of the coupling.

Figs. 17, 18, 19 and 20 illustrate still another form of joint. In this construction an ordinary quick screw connection is provided between the coupling 43 and the annular member 44, such quick screw connection comprising the series of threads 45 engaging corresponding grooves 46 in the member 44. The coupling 43 is also provided with a beveled surface 47 adapted to fit against the end of the member 44 when the coupling is secured into position.

Fig. 21 illustrates a construction quite similar to that of Figs. 17, 18, 19 and 20 the primary difference being that the beveled surface 48 on the coupling 49 is in advance of the screw-threads 50.

In the construction of Fig. 22 the ground joint 51 is in advance of the screw threads and recessed portions 52 alternate with sets of interrupted threads on the coupling member 54. The annular member 55 with which the coupling coöperates is of course correspondingly formed so that the coupling member can be slipped up inside the joint member and by a fraction of a rotation, the ground joint portions of the connection are brought tightly into contact. This form of joint can be very cheaply made as little machine work is necessary.

Having thus described my invention and illustrated its use what I claim as new and desire to secure by Letters Patent is the following:

1. The combination in a plumbing fixture including a soil pipe and a bowl, of a joint connection between the bowl and soil pipe comprising an annular joint member secured to the bowl around the outlet thereof, a coupling member secured at one end to the annular joint member and having its other end screw threaded externally, an end portion on the soil pipe into which the end of the coupling member is threaded, said end portion having at its outer end a recess surrounding the coupling and having its outer wall spaced away from the coupling so as to permit the tamping of packing material into the bottom of the recess, and a metallic packing for the recess.

2. The combination in a plumbing fixture including a soil pipe and a bowl, of a joint

connection between the bowl and soil pipe comprising an annular joint member secured to the bowl around the outlet thereof, a coupling member secured at one end to the annular joint member and having its other end screw threaded externally, an end portion on the soil pipe into which the end of the coupling member is threaded, said end portion having at its outer end a recess surrounding the coupling and having its outer wall spaced away from the coupling so as to permit the tamping of packing material into the bottom of the recess, and a metallic packing for the recess in the form of a soft metal member screw threaded onto the coupling and adapted to substantially fit the said recess when screwed into such recess preliminary to tamping.

3. The combination in a plumbing fixture including a soil pipe and a bowl, of a joint connection between the bowl and soil pipe comprising an annular joint member secured to the bowl around the outlet thereof and having locking means, a coupling screw threaded externally at one end and having locking means for coöperating with the other locking means at the other end, the locking means having an inclination such that a partial rotation of the bowl causes the coupling and joint member to be brought into tight engagement, an end portion on the soil pipe into which the end of the coupling is threaded, and a screw threaded packing member coöperating with the said end portion and threaded onto the threads of the coupling above its threaded connection with the said end portion of the soil pipe.

4. The combination in a plumbing fixture including a soil pipe and a bowl, of a joint connection between the bowl and soil pipe comprising an annular joint member secured to the bowl around the outlet thereof and having locking means, a coupling screw threaded externally at one end and having locking means for coöperating with the other locking means at the other end, the locking means having an inclination such that a partial rotation of the bowl causes the coupling and joint member to be brought into tight engagement, an end portion on the soil pipe into which the end of the coupling is threaded, said end portion having at its outer end a recess surrounding the coupling and having its outer wall spaced away from the coupling so as to permit the tamping of packing material into the recess, and a packing for the recess.

5. The combination in a plumbing fixture including a soil pipe and a bowl, of a joint connection between the bowl and soil pipe comprising an annular joint member secured to the bowl around the outlet thereof and having a ground surface and interrupted quick screw means, a coupling screw

4

threaded externally at one end and having at the other end a ground surface for engaging the other ground surfaces and quick screw means for engaging the other quick screw means whereby a partial rotation of the bowl causes the engagement of the ground surfaces, an end portion on the soil pipe into which the end of the coupling is threaded, said end portion having at its 10 outer end a recess surrounding the coupling and having its outer wall spaced away from the coupling so as to permit the tamping of packing material into the recess and a packing for the recess.

15 6. In combination in a plumbing fixture, a bowl provided with a circular outlet passage having an enlarged non-circular por-

tion at its end, a metal joint member with its periphery spaced from the side walls of the enlargement and having a non-circular exterior whereby its rotation is prevented and a circular interior, and a holding packing fitting between the periphery of the joint member and the surface of the enlargement, the joint member being provided with 20 25 screw means for securing it to a coupling.

In testimony whereof I have hereunto signed my name in the presence of the two subscribed witnesses.

IRA A. MANN.
